UNITED STATES PATENT OFFICE.

WALTER T. GORTON, OF THE UNITED STATES ARMY.

COMBINATION MOUNT FOR MACHINE GUNS.

Application filed August 20, 1925. Serial No. 51,463.

(GRANTED UNDER THE ACT OF MARCH 3, 1883; 22 STAT. L. 625.)

To all whom it may concern:

Be it known that I, WALTER T. GORTON, U.S. Army, a citizen of the United States, and a resident of Springfield, county of 5 Hampden, and State of Massachusetts, have invented an Improvement in Combination Mounts for Machine Guns, of which the following is a specification.

The invention described herein may be 10 used by the Government, or any of its officers or employees in prosecution of work for the Government, or by any other person in the United States, without payment to me of any royalty thereon, in accordance with the 15 act of March 3, 1883.

This invention relates to a combination mount for machine guns.

In the employment of machine guns for low angle firing against ground targets it 20 is desirable in the interest of stability and for the protection of the gun crew that the gun be mounted as low as possible while in high angle firing against aircraft a more elevated mounting is essential to proper aiming and manipulation of the gun.

The principal object of the present invention is to provide a combination mount without sacrifice of simplicity, compactness, stability and light weight.

To these and other ends, my invention consists in the construction, arrangement, and combination of elements, described hereinafter and pointed out in the claims forming a part of this specification.

A practical embodiment of the invention is illustrated in the accompanying drawings, wherein:

Fig. 1 is a view in side elevation of a mount constructed in accordance with the 40 invention and shown in the position of low mounting;

Fig. 2 is a plan view thereof with the gun removed;

Fig. 3 is a view in elevation showing the 45 gun in position of high mounting;

Fig. 4 is a vertical sectional view of the tripod head;

Fig. 5 is a sectional view on the line 5-5 50 of Fig. 4; and

Fig. 6 is a sectional view on the line 6-6 55 of Fig. 4.

Referring to the drawings by numerals of reference:

The amount is of the tripod type and com-

prises a central cylindrical head 5 to one 55 end of which are attached a pair of relatively long trail legs 6-6 and a shorter front leg 7. The legs are individually adjustable to provide for maintaining the axis of traverse vertical on uneven ground, for folding, 60 and for inverting the tripod.

In the normal application of the tripod for mounting a gun for low angle firing against ground targets, the joints of the legs will be at the upper end of the tripod 65 head. Rotatable in the head is a stem 8 provided with a yoke 9 for trunnioning the gun. By virtue of the split trail the gun may be normally trunnioned directly above the tripod head thus insuring a low stable mount- 70 ing.

Mounted on the lower end of the stem and held against the tripod head by a nut 10 is a lug 11 having an annular serrated 75 face 12. A pin 13 passing through the lug axially of the serrated face serves to mount for movement in elevation a cradle 14. The cradle terminates forwardly in a serrated disc 14' adapted to engage the serrated face 12 when the two are drawn together by means of a jamming handle 15 threadedly mounted on one end of the pin 13. The free end of the cradle constitutes a yoke 16 provided with apertures 17-17 80 adapted when the cradle is swung to the vertical position to receive the trunnion pin when the gun is to be mounted for high angle firing against aircraft. The yoke also serves to pivotally mount an elevating mechanism 18 of usual construction for supporting the rear end of the gun. The cradle serves to confine traversing movement between the trail legs thus insuring stability during firing by preventing the gunner from inadvertently moving the gun beyond the 95 spread of the trail legs.

In adjusting the tripod or mounting the gun for high angle firing against aircraft the mount is simply inverted, the cradle swung to the vertical position and the gun 100 trunnioned therein. The elevating mechanism is not used in this class of firing and hangs idle.

The mount including the cradle folds umbrella fashion making a compact and neat 105 unit for transportation while permitting it to be quickly erected in either position of adjustment.

While in the foregoing there has been illustrated and described such combination and arrangement of elements as constitute the preferred embodiment of my invention, 5 it is nevertheless desired to emphasize the fact that interpretation of the invention should only be conclusive when made in the light of the subjoined claims.

I claim:

- 10 1. A combination mount for machine guns embodying a central head, a pair of relatively long trail legs and a shorter front leg pivotally secured thereto adjacent its normal upper end, a stem rotatable in said head, a 15 yoke on the upper end of the stem for normally trunnioning a gun for low angle firing, a lug retained on the lower end of the stem, a cradle including a yoke pivotally secured to the lug, said cradle adapted to 20 be swung to the vertical position when the tripod is inverted to trunnion the gun in its yoke for high angle firing, and an elevating mechanism carried by the cradle yoke.
2. A combination mount for machine guns 25 embodying a central head, supporting legs pivotally secured thereto adjacent its normal upper end, a stem rotatable in said head, a yoke on the upper end of the stem for normally trunnioning a gun for low angle firing, a lug retained on the lower end of the 30 stem, a cradle including a yoke pivotally secured to the lug, said cradle adapted to be

swung to the vertical position when the tripod is inverted to trunnion the gun in its yoke for high angle firing, and an elevating 35 mechanism carried by the cradle yoke.

3. A combination mount for machine guns embodying a central head, supporting legs pivotally secured thereto, a stem rotatable in said head, a yoke on one end of the stem 40 for trunnioning a gun for low angle firing, and a pivoted cradle on the other end of the stem provided with means for supporting the rear end of the gun, said cradle adapted to be swung to the vertical position when 45 the mount is inverted to trunnion the gun for high angle firing.

4. A mount for machine guns embodying a central head, supporting legs pivotally secured thereto, a stem rotatable in said head, a yoke on one end of the stem for trunnioning a gun for low angle firing, and a pivoted cradle on the other end of the stem provided with means for supporting the rear end of the gun. 50

5. An invertible tripod embodying a head, means on one end for normally trunnioning a gun for low angle firing, and pivotally secured means on the other end adapted in one position of adjustment to support the 55 rear end of the gun and in another position of adjustment to trunnion the gun for high angle firing.

WALTER T. GORTON.
